US00D953939S

(12) **United States Design Patent** (10) Patent No.: **US D953,939 S**
Kermani (45) Date of Patent: ** Jun. 7, 2022

(54) **DRIFTING KART**(71) Applicant: **Ali Kermani**, Huntington Beach, CA
(US)(72) Inventor: **Ali Kermani**, Huntington Beach, CA
(US)(**) Term: **15 Years**(21) Appl. No.: **29/774,679**(22) Filed: **Mar. 18, 2021**

(57) **CLAIM**

The ornamental design for a drifting kart, as shown and described.

DESCRIPTION

FIG. 1 is a top, front, and left side perspective view of a drifting kart showing my new design;

FIG. 2 is a right side elevation view thereof;

FIG. 3 is a front elevation view thereof;

FIG. 4 is a rear elevation view thereof;

FIG. 5 is a top plan view thereof; and,

FIG. 6 is a bottom plan view thereof.

The broken lines in the drawings illustrate portions of the drifting kart that form no part of the claimed design.
